J. S. BOSWELL

JUG

Filed Oct. 23, 1926

UNITED STATES PATENT OFFICE.

JOHN S. BOSWELL, OF FORT WORTH, TEXAS, ASSIGNOR TO JERSEY-CREME COMPANY, OF FORT WORTH, TEXAS.

DESIGN FOR A JUG.

Application filed October 23, 1926. Serial No. 19,461. Term of patent 14 years.

To all whom it may concern:

Be it known that I, JOHN S. BOSWELL, a citizen of the United States, residing at Fort Worth, in the county of Tarrant and State of Texas, have invented a new, original, and ornamental Design for Jugs, of which the following is a specification, reference being had to the accompanying drawing, forming part thereof.

I claim:

The ornamental design for a jug, as shown.
